ABSTRACT: A method and apparatus for transferring a developed xerographic powder image from a photoconductive surface to a final support material such as paper by contacting the powder image with elastomeric material under pressure to encapture the developed powder image due to the deformation of the elastomeric member and then transferring the powder image from the elastomeric member onto a paper support material by heat and pressure. In one example of the invention the elastomeric member is in the form of a belt while in another example of the invention the elastomeric member is formed on a drum surface. The paper support material may be preheated in one case prior to the pressure transfer of the powder image or alternatively heat may be applied simultaneously at the contacting surfaces transferring the powder image from the elastomeric member onto the paper support material.

METHOD AND APPARATUS FOR OFFSET XEROGRAPHIC REPRODUCTION

This invention relates to method and apparatus for transferring a xerographic powder image from a xerographic plate to a support material and, in particular, to method and apparatus for transferring a high percentage of the xerographic powder.

More specifically, this invention relates to an improved method for transferring an extremely high percentage of a xerographic powder image from a photoconductive surface to a support material to produce what is herein referred to as a quality image transfer. In the process of xerography, a plate, comprising a conductive backing upon which is placed a photoconductive insulating material, is charged uniformly and the photoconductive surface then exposed to a light image. The photoconductive coating becomes conductive under the influence of the light image so as to selectively dissipate the electrostatic charge found thereon to produce what is known as a latent image. The latent image is developed by means of a variety of pigmented resins which have been specifically developed for this purpose. The pigmented resins, or, as herein referred to, "toners," are electrostatically attracted to the latent image on the photoconductive surface in proportion to the amount of charge found thereon. Areas of small charge concentration become areas of low toner density while areas of greater charge concentration become proportionally more dense.

The conventional method of transferring a developed xerographic image from a photoconductive surface to a support material is by electrostatic attraction. That is, a high electrostatic force field is created at the xerographic transfer station having a magnitude capable of overcoming the forces holding the xerographic powder image to the photoconductive surface. Electrostatic transfer is, as attested to by its commercial acceptance, a highly satisfactory means of transferring a developed xerographic image, to a paper support material. A corona generating device is positioned at the transfer station to impart an electrical charge to the paper support material of sufficient strength to attract toner particles from the photoconductor. The magnitude of the charge required to effect image transfer is dependent upon many variables. It has been found, however, that because of the nature of the electrostatic transfer operation some residual developing material remains behind on the photoconductive surface after transfer. That is, the electrostatic transfer force applied to the support material effects transfer of a preponderance of the developed powder image but some toner particles, possessing a higher magnitude of force than the electrostatic transfer force, remain behind on the photoconductive surface.

As can be seen, high quality image transfer in which fine details and halftones are discernable cannot be efficiently produced by conventional electrostatic transfer means because some of the image is left behind during the transfer operation. Furthermore, the removal and handling of residual toner left on the plate surface creates another unwanted problem in xerography.

With the advent of new xerographic techniques and materials, it is now possible to xerographically expose and develop images of finer detail than had heretofore been possible. However, these high quality images are of little value unless they can be efficiently transferred to a support material. That is, if part of the image is left behind during the transfer operation, the quality of the copy produced will be reduced by the amount of the residuum found on the plate surface.

It is therefore an object of this invention to improve method and apparatus for transferring a developed xerographic powder image from a photoconductive surface to a support material.

It is another object of this invention to transfer a xerographic powder image from a photoreceptor surface to a support material with a minimum of image degradation.

Another object of this invention is to improve method and apparatus for effecting high-quality image transfer of a developed xerographic image.

A still further object of this invention is to transfer substantially all of a developed powder image from a photoconductive surface to a final support material.

Yet another object of this invention is to reduce the amount of residual toner on a xerographic plate after transfer.

These and other objects of this invention are attained by a method and apparatus capable of initially removing an extremely high percentage of a developed xerographic image from a photoreceptive surface by encapturing the image in a resilient, heat-resistant, intermediate blanket and transporting said image to a remote final transfer station. At the second or final transfer station, the image is transferred from the intermediate blanket to a support material by means of a heat transfer operation.

For a better understanding of the invention as well as other objects and further features thereof, reference is had to the following detailed description of the invention to be read in connection with the accompanying drawings, wherein:

FIG. 1 is a schematic sectional view of a conventional type of xerographic processing machine adapted to perform the two-step transfer method of the present invention;

FIG. 2 is a schematic embodiment of the present invention in which a transfer blanket is shown in drum configuration; and

FIG. 3 is another partial embodiment showing a conductive heating means at the final transfer station.

FIG. 1 shows an automatic xerographic apparatus employing a photoconductive surface which is formed in drum configuration. The drum 10 comprises a photoconductive light-sensitive receiving surface 11 which is placed on a conductive backing 12. The drum is mounted on shaft 13 journaled in a machine frame (not shown) so as to rotate in a clockwise direction as indicated by the arrow. Rotation of the drum causes the drum surface to sequentially pass a plurality of xerographic processing stations. The drum is rotated at a constant rate through the action of synchronous drive motor 14.

For the purpose of the present disclosure, the several xerographic processing stations in the path of movement of the drum surface may be described functionally as follows:

45 A charging station 15 at which a uniform electrostatic charge is deposited on the photoconductive layer of the xerographic drum;

An exposure station 16 at which a light image or radiation pattern of copy to be reproduced is projected onto the drum surface to dissipate the drum charge in the exposed areas thereon so as to form a latent electrostatic image of the copy to be reproduced;

A developing station 17, at which point, triboelectrically charged toner particles are brought into close proximity to the oppositely charged latent image found on the photoconductive surface. The oppositely charged toner particles are attracted to the charged areas on the drum surface thereby developing the latent image;

A transfer station 18 where the xerographic powder image is electrostatically transferred from the drum surface to an intermediate support material; and,

A drum-cleaning and discharge station 19 capable of removing residual toner particles found on the drum surface after transfer.

In general, the charging apparatus located at station 15 may be of the type disclosed in Walkup U.S. Pat. No. 2,777,957, and includes a corona discharge array 20 of one or more corona discharge electrodes that extend transversely across the drum surface and are energized from a high-potential source (not shown) and are substantially enclosed in a shielding member 21. The drum, which is being rotated past the charging station, is sprayed with sufficient charged ions to uniformly charge the drum surface at a relatively high potential.

subsequent thereto in the path of motion of the xerographic drum, is exposure station 16. This exposure station is one of a number of types of mechanisms or the like used to project a light image of the copy onto the conductive surface. An original document is placed on belt 22 and the transport is driven at synchronous speed by xerographic drum surface by means of motor 23. A source 24 illuminates the original document and the light is transported through optical system 25 and placed on drum system at scanning slit 26. A prism 9 reverses the image and reflects it through the slit 16 onto drum 10. Adjacent to the exposure station is developing station 17. The upper housing 27 contains a lower sump portion 28 in which an accumulation of developing material is housed. A belt-type conveyor 29, having a suitable driving means by motor 30, is used to transport the developing material from the upper part of the developer housing where it is cascaded over a hopper chute onto the xerographic drum. As the toning material is cascaded over the drum, toner particles are electrostatically attracted from the carrier component of developer material to the drum surface to develop the image found thereon. Denuded carrier particles flow from the drum surface and are once again returned to the upper-housing sump. As toner images are formed, additional toner particles may be supplied to the developer material in proportion to the amount of toner deposited on the drum. For this purpose there is provided a container 31 by which toner 32 can be added to the developing material as needed, toner being added at a rate determined by control gate 33. After development, the image thus formed is transferred at station 18, the operation of which will be explained in further detail below.

The final station in the present device is a drum-cleaning discharge station where residual powder, if any, which remains on the xerographic drum after transfer is removed by cleaning brushes 35 driven by motor 37. A conditioning iron is positioned adjacent to the cleaning brushes which removes the residual toner remaining on the drum with ions having a charge opposite to that of the residual toner. This charge tends to neutralize the residuum thereby making the highly efficient drum cleaning. It should be noted that the cleaning station, as shown in this preferred embodiment, is eliminated in the present invention because of the efficiency of the transfer operation.

Basically, the transfer operation of the present invention is carried out in two distinct steps. Initially, the xerographic image is pressure transferred from a photoreceptor to an intermediate blanket, the blanket being adapted to mechanically remove a powder image from a xerographic drum. The transfer blanket is described in further detail below. The intermediate blanket is then transported to a final transfer station located at any suitable distance from the plate surface. Since the toner powder is mechanically affixed to the blanket, the distance in time and transit to the final support station is no way restrictive. A wide flexibility in machine configuration is thereby afforded by use of this intermediate transfer blanket. The final transfer step to a final support material is accomplished by a heat transfer operation in which the xerographic powder is melted sufficiently to bond to the support material.

The transfer blanket is constructed of a heat-resistant material having a resiliency such that the blanket is able to wrap around xerographic powder particles making up a xerographic image. The blanket is biased into contact with an image-bearing plate with sufficient force to cause deformation of the blanket material. The biasing force is then released and the deformed blanket begins recovery. However, complete recovery is prevented by the particulate material enfolded or trapped therein. Sufficient holding force is exerted by the transfer blanket material upon the powder particles to overcome the heretofore mentioned mechanical and electrostatic forces holding them to the plate. The powder image enfolded in the transfer blanket material is removed from the plate with the transfer blanket.

5 Blankets, similar to the one herein described, have been made by casting a silicone gum rubber on a soft metal substrate such as aluminum or brass to form an endless belt. Developed images having resolutions in the nature of 40 line pairs per millimeter have been transferred to the silicone blankets using a pressure of between 5 and 10 lbs. per linear inch. It was found that about 95 percent image transfer was effected at transfer speed in excess of 20 inches per second. Blankets having a hardness of between 15 and 35 durometers were tested under the above mentioned conditions with little noticeable effect on the quality of the transfer or the efficiency of the operation. A gum rubber suitable for use as a transfer blanket material is manufactured by the General Electric Company under the trade name RTV-615A.

10 Referring once again to FIG. 1, a pickoff blanket 40 is shown positioned in the transfer station 18. Blanket 40 acts as an intermediate support material to which a developed xerographic image is transferred from drum 10 during the first step of the two-step transfer operation. A drive motor 43, acting through drive roller 44, moves the blanket at synchronous speeds with the peripheral drum surface so that no relative motion exists between the two which could cause offsetting of the image during the initial transfer step. Although not shown, any convenient belt-tensioning device can be employed to prevent belt slippage during the transfer operation. A pair of rollers 41 and 42, respectively, hold the blanket in contact with the drum surface over a portion of the drum arc. The rollers are biased into contact with the drum by means of a pressure-exerting element 45. The pressure-exerting element is housed within a casting 46 permanently affixed to the machine frame. The pressure-exerting element comprises a regulating screw 47 positioned on shaft 48. By turning control knob 49, located at the end of shaft 48, the position of bifurcated member 50 can be adjusted to control the amount of force exerted upon the blanket. Part of shaft 48 is surrounded by a compression spring 51 which acts upon the rollers to supply the necessary biasing force.

15 The final support material employed in the preferred embodiment is paper web 55. Roll 56 supplies a continuous web of support material to a series of feed rollers 57 and 58, respectively. The feed rollers guide the paper support material into contact with the intermediate image bearing transfer blanket. A pressure roller 59 which is also being driven at the same peripheral speed of the blanket, is mounted in close proximity to the blanket and is adapted to urge the paper support material into pressure contact therewith. The movement of the web material is synchronized with the movement of the blanket by means of drive motor 60 acting through pickup roll 61. Positioned adjacent to the point of contact between the support material and the transfer blanket is a heating unit 61. The heating unit is positioned so that the web of support material is placed in thermal contact therewith prior to its contacting the image-bearing support blanket. Sufficient heat energy is transferred to the support material to cause the xerographic powder to melt or partially melt when brought into contact therewith. Although heating unit 61 is of the oven-type, it should be clear that any heating device capable of raising the temperature of the support material to a level sufficient to effect transfer of a xerographic powder image can be so utilized.

20 It should be noted that the silicone rubber blanket is adhesive by nature. On the other hand, a paper support material is made of fibrous material to which heated toner particles will readily bond. A relatively small force normal to the blanket surface is all that is required to separate the heated xerographic powder image from the adhesive blanket. Although it is contemplated that sufficient heat energy will be transferred during the final transfer operation to produce fusing of the image to the final support material, it is, however, quite feasible to obtain transfer to the final support material at temperatures below the fusing temperature of the toner.

25 FIG. 2 is a modified embodiment of the present invention in which the transfer blanket 40 is mounted in drum configuration. Drum 70 is rotatably mounted in the machine frame (not

shown) and driven at the same peripheral speed as the xerographic drum 10. The intermediate transfer drum is biased into contact with the xerographic drum thereby effecting a pressure transfer as previously described. The image is next transported to a final transfer station 72. The paper support is shown being guided through the final transfer station by means of guide rolls 57 and 58. A roller 71 capable of being heated internally is positioned at the final transfer station and is mounted in close proximity to drum 70 so that a paper support 55 passing therebetween is pressed into contact with the transfer blanket 40. It has been found that a combination of heat and pressure, as herein described, produces a rapid and efficient transfer of the powder image to the final support material. A 100 percent image transfer to a paper support material has been produced at transfer speeds in excess of 20 inches per second by contacting the nonimage side of the paper support material with a roll being maintained at a temperature of 450° F. while applying a pressure of 100 lbs. per linear inch.

Oftentimes these relatively high-transfer temperatures cannot be utilized because of the nature of the support material being processed. It is therefore desirous to utilize lower temperatures during the final heat transfer step.

Referring now to FIG. 3, a partial schematic of a modified embodiment of the final transfer operation is shown therein. A heater 80, comprising a heat-insulated enclosure 81 and a curved heat transfer station 82, is shown positioned immediately below transfer blanket 40 in the final transfer station. The heat transfer surface 82 is made of a relatively smooth material having high thermal conductivity over which support material 55 can be readily advanced. The heat transfer surface is convexed upwardly with an appropriate curvature so that the advancing support material is forced into close sliding contact therewith thereby producing good conductive heat flow between the two contacting surfaces. A heat source 83 is positioned internal the heater enclosure and is operatively connected to control means (not shown) to maintain the heat transfer surface at a predetermined temperature level.

Blanket 40 is brought into close proximity with the heat transfer surface by means of rollers 84 and 85. The web of support material 55 which is being guided over the heated platen surface by rollers 57 and 58, respectively, is forced into close sliding contact with the curved platen surface by the transfer blanket. Heat is conducted through the support material to the exposed portion of the xerographic powder image and trapped within the blanket material. Sufficient heat is transferred to the powder image to cause it to coalesce or adhere to the paper support material with sufficient strength so that image separation is effected when the paper is removed from contact with the blanket.

It should be noted that the two-step transfer operation of the present invention is extremely well suited to effect image transfer anywhere around the drum periphery. Although the initial transfer step is shown taking place at the 6 o'clock position, it should be clear that the present apparatus is in no way so restricted. Initial transfer at any drum position is quite feasible. A further advantage of this transfer method is its capability of transporting a powder image to a remote final transfer station thereby enabling the paper handling equipment, fusing equipment and the like to be conveniently located at some distance from the photoreceptive surface. In other words, the present invention enables quality transfer to be performed at stations remote from a xerographic drum or the like thereby giving a wide freedom of machine design heretofore unknown in the art.

While this invention has been described with reference to the structure disclosed herein, it is not confined to the details as set forth, and this application is intended to cover such modifications or changes as may come within the purposes of the improvements or the scope of the following claims.

I claim:

1. The method of transferring a heat-fusible powder image of toner particles from a xerographic plate to a paper support material including

5   pressing a resilient member into contact with the image-bearing xerographic plate with sufficient force to cause the member to deform about the powder image, releasing the deforming pressure exerted on said member whereby the powder particles forming the image are enfolded within the resilient member

10   applying sufficient heat energy to a paper support material such that upon contact with the powder image enfolded in said member the toner particles melt,

15   immediately contacting the toner particles with the paper support material causing the toner particles to melt and coalesce and transfer from the member to the support material.

20   2. The method of claim 1 wherein said support material is maintained at a temperature sufficient to cause the powder image to fuse to the support material when contacted therewith.

25   3. The method of claim 1 wherein said resilient member is comprised of a silicone gum rubber having a hardness ranging from about 15 to about 35 durometers cast on a flexible substrate.

30   4. The method of claim 3 wherein the heat-fusible powder image is heated to a temperature below its fusing temperature

35   5. The method of claim 4 having the further step of pressing the support material into contact with said member with sufficient force to fix the powder image to the support material.

40   6. In the process of xerography wherein an electrostatically charged xerographic plate is exposed to a projected light image to form an electrostatic latent image on the plate corresponding to the projected image and the plate is developed with heat-fusible toner particles attracted to the latent image to form a xerographic powder image corresponding to the projected image, the method of transferring and fixing the powder image to a paper support material comprising

45   pressing a silicone rubber member into intimate contact with the powder bearing xerographic plate with sufficient force to cause the member to deform around said image, releasing the deforming force exerted on said member whereby the recovering resilient member enfolds the powder image therein,

50   removing the image-bearing resilient member from the xerographic plate,

55   heating a paper support material to a temperature sufficient to melt said xerographic powder when brought into contact therewith; and

60   immediately pressing the heated paper support material into intimate contact with the image bearing resilient member with sufficient force to cause the powder image to adhere to the support material and become fixed thereto.

65   7. Apparatus for transferring a xerographic powder image of toner particles from a photoconductive plate to a paper support material and fixing the image thereon including

70   a resilient member arranged to be placed in contact with the photoconductive plate,

75   means to exert a bias pressure on the resilient member into pressure contact with the photoconductive plate with sufficient force to cause the member to deform about the powder image for a predetermined time and then to release the deforming pressure exerted on said member whereby the member recovers sufficiently to entrap powder particles therein,

80   means for transporting a paper support material into contact with the member carrying powder particles, and

85   means to raise the temperature of the paper support material sufficiently immediately before contact of the support material with the powder particles such that upon contact said powder particles are transferred from the resilient member to the support material and fixed thereon.

90   8. The apparatus of claim 7 wherein said member comprises silicone gum rubber having a hardness ranging from about 15 to about 35 durometers.

9. Apparatus for transferring xerographic powder image from a rotating photoconductive drum to a final support material and fixing said powder image to the final support material including
 a resilient member being arranged to contact the photoconductive drum,
 drive means for moving said member at the same peripheral speed as the drum,
 means to place the resilient member into pressure contact with the drum with sufficient force to cause the member to deform about the powder image for a predetermined time and then, to release the deforming pressure exerted on said member whereby the member recovers sufficiently to entrap powder particles therein,
 means to move a final support material into contact with the powder image enfolded in said member, and
 means to heat the xerographic powder image while in contact with the final support material whereby the powder

image coalesces to the final support material.
 10. The apparatus of claim 9 wherein said member comprises silicone gum rubber.
 11. The apparatus of claim 10 wherein said member is supported on a cylindrical drum.
 12. The apparatus of claim 10 including means to raise the temperature of the final support material to a level whereby the powder image being transferred is fused to said support material.
 13. The apparatus of claim 11 having further means to force the final support material into contact with the silicone gum rubber member with sufficient pressure to cause the heated toner to bond to the final support material.
 14. The apparatus of claim 10 wherein the final support material is held in contact with the silicone rubber member by a heated platen arranged to support the nonimage side of the support material in sliding contact.
